(57) **CLAIM**

The ornamental design for a cockpit and center console for vehicles, as shown and described.

DESCRIPTION

FIG. 1 is a left front perspective view of a cockpit and center console for vehicles showing my new design;

FIG. 2 is a front elevational view thereof; and,

FIG. 3 is a right front perspective view thereof.

The structural features depicted by broken lines have been shown to illustrate portions of the cockpit and center console for vehicles that form no part of the claimed design.
